2-AZIDOCYCLOHEXANONE OXIME

Theodor Weil, New Brunswick, and Hugo Stange, Princeton, N.J., assignors to FMC Corporation, New York, N.Y., a corporation of Delaware
No Drawing. Filed Oct. 23, 1965, Ser. No. 504,069
1 Claim. (Cl. 260—349)

ABSTRACT OF THE DISCLOSURE

The new compound, 2-azidocyclohexanone oxime, is a hypotensive agent that can be safely administered to mammals for an extended period of time in an amount sufficient to lower blood pressure, particularly the diastolic pressure.

This invention relates to the control of blood pressure in mammals and aims to provide a new hypotensive agent.

The prevalence and persistence of hypertension and the serious physical disorders that are associated therewith have prompted extensive searching for chemotherapeutic agents which can be safely administered over an extended period of time to reduce blood pressure, particularly diastolic pressure, without producing untoward toxic manifestations or deleterious side effects. It is highly desirable that a hypotensive agent exhibit, not only low toxicity and absence of side effects, but also long duration of activity and smoothness and stability of action so that the desired reduction of blood pressure may be achieved through the administration of substantially constant dosage levels of the drug which will continue to be effective over the longest possible intervals. The search for a hypotensive agent having such properties has not been entirely successful.

We have discovered that the hitherto unknown compound 2-azidocyclohexanone oxime is a stable hypotensive agent of very low toxicity which exhibits smooth and prolonged activity of a high order. This was surprising because various azides have been included among the compounds that have been tested for hypotensive activity. For instance, the use of sodium azide is well known but this compound is quite toxic. Different organic azides have also been tested in the past by others who have reported that they have found them to be ineffective or too fleeting in their action or of insufficient potency to permit their use as effective hypotensive agents. Hence, the organic azides could not have been regarded as a promising field within which a superior hypotensive agent might be found.

Our new compound is particularly noteworthy in the respect that moderate increases in the size of a non-toxic but effective dose thereof will result in a proportionate increase in the degree and duration of hypotensive effect and without an observable increase in toxic manifestation. The low order of toxicity of our new compound has been established as follows:

Charles River male albino rats, weighing from 200 to 400 grams were used. The rats were divided into groups of 5 rats each and administered the test compound orally at logarithmic increments in a manner intended to bracket the 50 percent lethal dosage.

The compound was suspended in an aqueous dispersion of 1 percent methylcellulose (Methocel) and administered at a constant volume of 2 ml./100 grams of body weight at all dosage levels.

All rats were fasted for 16 hours prior to administration of the compound.

All animals were observed for evidence of pharmacotoxic signs and mortality at periodic intervals immediately after administration and daily thereafter for a total period of 14 days.

2

Necropsy evaluations were made of all rats which succumbed during the observation period.

No lesions were observed at necropsy which could be attributed to an effect produced by the administration of our new compound.

Lesions not related to the compound included congestion, pinpoint hemorrhages and pneumonia in 4 of the 11 rats examined.

The acute oral LD_{50} data appears in Table 1.

TABLE 1.—ACUTE ORAL LD_{50} VALUES 2-AZIDOCYCLOHEXANONE OXIME IN ALBINO RATS

10	No. Dosed/No. Dosed Dosage Level (mg./kg.)							LD ₅₀ and Confidence Limits (mg./kg.)
	215	316	464	681	1,000	1,470	2,150	
15	0/5	0/5	0/5	-----	0/5	0/5	0/5	1,120 (963-1,310)

20 To test the hypotensive activity of our new compound, arterial blood pressure in pentobarbitalized (35 mg./kg.) normotensive mongrel dogs of either sex was recorded from the left or right cannulated femoral artery via a heparinized saline bridge to a Statham P-23Db low volume displacement or a Bourdon photoelectric pressure transducer which in turn was connected to an electronic recorder. The contralateral femoral vein was isolated and cannulated for injection of the test compound and control substances.

25 30 A midline incision was made in the cervical area of the neck and the trachea was isolated and cannulated to produce a free airway. Both carotid arteries were exposed for later occlusions. The right vagus nerve was divided and the peripheral stump passed through tubular platinum electrodes for later stimulation.

35 40 One-half hour was allowed to elapse after dividing the vagus nerve to permit the animal to recover from surgery and the blood pressure to stabilize. Prior to the intravenous administration of 2-azidocyclohexanone oxime at least two control responses were obtained through the following procedures:

- (1) Acetylcholine chloride, 2 mcg./kg., intravenously administered.
- (2) Histamine phosphate, 4-5 mcg./kg., intravenously administered.
- (3) L-Epinephrine bitartrate, 2 mcg./kg., intravenously administered.
- (4) Angiotensin II (hypertensin), 1 mcg./kg., intravenously administered.
- 50 (5) Peripheral vagal stimulation, 5-15 seconds.
- (6) Bilateral Carotid occlusion, 15-30 seconds.

55 The control series was administered at least twice prior to injection of the test compound. The control series was periodically applied after administration of the compound as long as an effect persisted on the blood pressure.

60 Our new compound is soluble in polyethylene glycol (Carbowax 300), and was prepared for intravenous administration by dilution in this vehicle to a 25 percent weight/volume concentration. A quantity of our new compound, solubilized in this manner was further diluted as necessary so that each dosage level administered would not exceed 2 ml. in volume in any one single administration. Comparable volumes of the solvent without compound were periodically administered for control purposes in each experimental trial. Our new compound was individually administered in dosages of 1 to 20 mg./kg. to at least two dogs.

65 70 A dosage of 1 mg./kg. decreased the mean arterial blood pressure 14 percent for 120 minutes. Increase in dosage proportionately increased the degree and duration of effect in a dose-dependent fashion.

Bradycardia (10 to 20 percent) was produced at all three dosage levels. There was no change in respiratory rate or pattern.

Acetylcholine and histamine depressor responses and BCO pressor responses were inhibited or blocked for about 1 hour at 1 and 10 mg./kg. dosages (same dog). However, at 5 mg./kg. in another animal these responses were only mildly inhibited. Epinephrine and angiotensin pressor responses were inhibited in the first animal, but not in the second.

TABLE 2.—DEPRESSOR POTENCY AND DURATION OF ACTION OF 2-AZIDOCYCLOHEXANONE OXIME ON THE MEAN ARTERIAL BLOOD PRESSURE OF ANESTHETIZED NORMOTENSIVE MONGREL DOGS

Dog No.	Dose, mg./kg.	Mean Arterial Blood Pressure (mm. Hg.)			Duration (min.)
		Control	Change	Percent change	
234	1	147	-14	10	120
236	5	153	-24	17	>300
234	10	152	-74	49	240

Further test results are set forth in the following table:

TABLE 3.—BLOOD PRESSURE LOWERING EFFECTS

Dog No.	Dose (mg./kg.)	Mean Arterial B.P. (mm. Hg.)			Duration (min.)
		Control	Fall	Percent fall	
247	0.25	120	-12	10	30
245	0.25	123	-33	27	71
Mean			-22	18	50
250	0.5	145	-18	13	32
251	0.5	133	-8	6	114
Mean			-13	10	73
245	1.0	128	-50	39	38
234	1.0	157	-24	15	119
247	1.0	103	-11	10	110
Mean			-28	21	89
250	2.0	155	-38	25	168
251	2.0	135	-28	21	>300
Mean			-33	23	>234

In order that our invention will be fully available to those skilled in the art, the preparation of our new compound is briefly described:

A concentrated aqueous solution of 6.9 g. hydroxylamine hydrochloride and 5.3 g. anhydrous sodium carbonate was prepared. To it, 13 g. of 2-azidocyclohexanone and enough ethanol to make a clear solution were added. After stirring for 24 hours at room temperature, the mixture was poured into excess water. The oil formed was extracted with CH_2Cl_2 . After drying over Na_2SO_4 , the

solvent was stripped and the residue distilled in a short path evaporative distillation apparatus at 60°C . and 0.05 mm. Hg to yield approximately 10 g. of a clear oil.

Cal.: C, 46.74; H, 6.54; N, 36.34. Found: C, 46.81; H, 6.63; N, 36.64.

2-azidocyclohexanone oxime of this invention may be administered intravenously, orally, or as an inhalant or spray. For oral administration, the compound may be associated with a solid pharmaceutical vehicle in the form of a tablet, pill, powder, capsule or other dosage unit form which is suitable for oral administration. Suitable solid vehicles include lactose, cornstarch, microcrystalline cellulose, talc, stearic acid, magnesium stearate, gums and the like. Coated tablets or pills are particularly suitable since the coating will prevent evaporation of the liquid azide from the pharmaceutical carrier. Capsules are also particularly suitable for the same reason. Typical pharmaceutical capsule casings such as gelatin may be used.

2-azidocyclohexanone oxime may also be administered in liquid form. For oral use, liquid emulsions or suspensions containing about 5-50% azide in water are suitable. Conventional emulsifying and suspending agents can be added as stabilizers. These compositions can also contain a small amount of ethanol which will partially dissolve the azide. Liquid fats are unsuitable as vehicles since the azides are highly soluble in these fats and apparently tend to remain dissolved in the chyle.

For intravenous injection or oral use, the azide can be used full strength, dissolved in ethanol, polyalkylene oxide or some other pharmacologically inert vehicle in which the azide is soluble. For intravenous injection it may also be emulsified in an inert aqueous isotonic solution. Azide concentrations of about 15-75% are suitable. The azide may also be administered by inhalation or nasal spraying but is normally not used in this manner because of the difficulty in controlling dosage. However, in acute situations where immediate reduction in blood pressure is necessary, inhalants and sprays are appropriate.

What is claimed is:

1. 2-azidocyclohexanone oxime.
